UNITED STATES PATENT OFFICE.

CHARLES A. FURTAW, OF PHILADELPHIA, PENNSYLVANIA.

RESPIRATORY MASK.

1,127,612.

Specification of Letters Patent.

Patented Feb. 9, 1915.

Application filed January 21, 1914. Serial No. 813,382.

To all whom it may concern:

Be it known that I, CHARLES A. FURTAW, a citizen of the United States, residing at Philadelphia, in the county of Philadelphia and State of Pennsylvania, have invented certain new and useful Improvements in Respiratory Masks, of which the following is a specification.

My invention relates to improvements in respiratory masks, the object of the invention being to provide a mask which may be comfortably worn, and which will insure a supply of pure dust filtered air, so that work may be readily done under trying conditions which now prove dangerous to workmen.

A further object is to provide a mask of the character stated in which an improved arrangement of valves is provided, allowing free respiration and insuring an escape of air exhaled from the lungs, supplying fresh air for inhalation.

A further object is to provide improved means for supplying air in a filtered condition either under normal atmospheric conditions or under pressure as desired.

With these and other objects in view, the invention consists in certain novel features of construction and combinations and arrangements of parts as will be more fully 30 hereinafter described and pointed out in the claims.

In the accompanying drawings: Figure 1 is a view in side elevation illustrating my improvements. Fig. 2 is a view in vertical 35 longitudinal section through the mask. Fig. 3 is a fragmentary view in horizontal section on the line 3—3 of Fig. 2. Fig. 4 is a similar view in section on the line 4—4 of Fig. 2, and Fig. 5 is a view in longitudinal 40 section through the center of the air filtering chamber taken on the line 5—5 of Fig. 1, but omitting the hose connection.

My improved mask 1 is composed in the main of leather having a transparent section 2, through which the user may readily observe the surroundings. The mask 1, or at least the face portion thereof, is outlined throughout its edge on its inner surface with relatively heavy felt 3 so as to snugly fit the 50 face and render the mask substantially air tight.

Canvas sections 4 are secured to the mask and are connected by suitable straps 5 at the back of the head to hold the mask in place. 55 The mask at its front is provided with a screened outlet 6 which is located at the outer

end of an inwardly projecting tube 7, the latter having its inner end located at an angle and provided with a flap valve 9 preferably of leather. This valve 9 is secured at its upper edge, and is free to swing inwardly, the inward movement of the valve limited by an internal flange 10 on the inner end of the tube 7 which serves to seat the valve and prevent any entrance of air 65 through the tube.

The tube 7 and the screen 6 are secured to metal plates 11 and 12, and the latter are secured to the leather of the mask by rivets 13, the mask being cut out to accommodate the 70 parts, which is of course to be understood.

The lower or chin portion of the mask is provided with an inlet nipple 14 having a flap valve 15 at its upper end, secured to the bottom portion of the mask as shown at 16 75 and free to swing upwardly to allow an entrance of air through the nipple.

17 represents an air filtering tank which is preferably secured around the waist of the user by means of a strap 18. This air 80 filtering tank is elongated and comprises telescopic sections 19 and 20 which clamp between them a sheet 21 of woven material. This sheet may be readily replaced by separating the sections.

The bottom of the lower telescoping section 20 is closed by a wire screen 22, and a nipple 23 is provided in the top of upper section 19 which is connected by a hose 24 with nipple 14, so that air which is drawn 90 into the mask is drawn through the wire mesh screen 22, and through the sheet 21. The screen 22 excludes the larger particles of dust, while the sheet 21 holds back the smaller particles, and hence the air passing 95 to the mask is thoroughly filtered.

At one end of the upper section 19 of tank 17, I provide an inlet 25 normally closed by a plug 26. This inlet is adapted to be connected by a hose with any air supply device, 100 so that if desired, air under pressure may be supplied to the mask.

By the arrangement of parts above described, if the pressure of air is excessive, and more than desired, it will escape past the valves 15 and 9, and through the screened outlet 6 and also will pass downwardly through the screened bottom 22 of tank 17.

In operation, the air inhaled is drawn upwardly through the filtering tank 17 and 110 hose 24 past valve 15. Air exhaled is forced outwardly past valve 9 through screened

opening 6. The inhalation causes valve 9 to close and valve 15 to open, and exhalation causes valve 15 to close and valve 9 to open. The valves therefore operate automatically and compel foul air which has been exhaled to escape and always permit, and in fact compel, the operator to breath fresh air continuously.

By reason of the arrangement of parts above described, the user may breathe through the mouth or nose, or both, and the device will operate with equal facility.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A respiratory mask constructed to fit the face and having a screened outlet in its front, an inwardly projecting tube communicating with the outlet and having its inner end at an angle to its longitudinal axis, a valve at the inner end of the tube permitting

the flow of air outwardly through the tube, said mask having an inlet in its lower end, and a flap valve permitting the flow of air into the mask through said inlet, substantially as described.

2. A respiratory mask of a shape to fit the face and having a lining of soft material to bear against the face, means on the mask for clamping the same around the head of the user, said mask having openings in its front and lower end, metal plates secured to the inner and outer surfaces of the mask and having a screen therein located over the opening in the front of the mask, a tube secured to the inner metal plate and having its inner end at an angle to its longitudinal axis, a flap valve in the tube normally closing the inner end of the tube, and a flap valve normally closing the opening in the bottom of the mask, substantially as described.

In testimony whereof I have signed my name to this specification in the presence of two subscribing witnesses.

CHARLES A. FURTAW.
